DESCRIPTION

FIG. 1 is a perspective view of the nailer.

FIG. 2 is a left side elevational view thereof.

FIG. 3 is a right side elevational view thereof.

FIG. 4 is a top view thereof.

FIG. 5 is a bottom view thereof.

FIG. 6 is a front elevational view thereof; and,

FIG. 7 is a rear elevational view thereof.

The broken lines illustrate portions of the design that are unclaimed. The broken lines and structure they depict form no part of the claimed design.
